UNITED STATES PATENT OFFICE.

ALBERT BODDEKER, OF CHICAGO, ILLINOIS.

BURNER APPARATUS.

Application filed November 28, 1927. Serial No. 236,252.

My invention relates, more particularly, to oil burning apparatus of the type involving, as an element thereof, a part which, to properly function, must extend in horizontal position, such as for example a generator plate to which the fuel oil is fed and over which the oil flows as exemplified in my United States Letters Patent No. 1,627,267, granted May 3, 1927.

10 The invention relates further to burner structures which are set into the lower portions of furnaces and are sealed therein against flow of air upwardly into the furnace about the burner, except through such 15 openings as may be intentionally provided for supplying air to the burner, an exemplification of such an arrangement being disclosed in my said Letters Patent, in which case air ducts opening through the bottom 20 of the burner structure and extending upwardly into a position to be heated by the combustion of the fuel at the burner and supplying heated air to the burner, are provided.

25 In such structures it is very difficult, if not impossible, in some instances, to effect the proper leveling of the parts, such as the generator plate referred to, required to be level to properly function, and once installed and 30 sealed no further adjustment of the burner structure to level such parts, either initially or later in case of displacement or replacement after removal, as for example for repair or cleaning, is possible.

35 My primary object is to provide burner structures of such construction that they may be properly sealed into furnaces and still permit of the accurate leveling of the parts required to be in level condition either 40 initially after sealing or later, as in the case of displacement or replacement after removal.

Another object is to provide a simple and economical structure of burner apparatus 45 which may be readily installed in a furnace and sealed in position therein; and other objects as will be manifest from the following description.

Referring to the accompanying drawings:

50 Figure 1 is a view in sectional elevation of the lower portion of a furnace shown as equipped with my improvements shown in elevation and partly sectional; and Figure 55 2 is a plan diagrammatic view of parts of the structure of Fig. 1, this view showing the

base of the burner structure in plan as viewed from section line 2 on Fig. 1 and in the direction of the arrow, supplemented by a 60 showing in plan, partly by dotted lines and partly by full lines, of certain parts above the section line.

The burner structure proper shown, which is of the general type disclosed in my said Letters Patent and functions in the same 65 way, comprises a base portion 3 and a superposed manifold portion 4 shown as supported thereon, the base portion 3 being formed at its center with an inverted bell portion 5. The bell portion 5 is centrally 70 apertured as represented at 6 and screwed into the opening thus provided is a pipe section 7 containing a series of radially disposed openings 8 in its side wall opening into the interior of the bell 5. Screwed upon the 75 upper end of the pipe section 7, and vertically spaced from the bottom of the inverted bell portion 5, is a burner head in the form of a generator plate 9 preferably of the circular stepped form, as shown, with the upper 80 surface of each annular step portion annularly grooved as represented at 10, this being the part of the burner structure shown which it is required be in level position to cause the burner to properly function. The 85 generator plate 9 contains a centrally disposed aperture 11 in which the open, upper, end of an oil pipe 12 is secured, the oil to be gasified being supplied to the upper surface of the plate 9 through this pipe which latter 90 extends downwardly through the pipe 7 and in spaced relation thereto as shown.

A pipe section 5^a screws at its upper end into the lower end of the opening 6 in the bell 5 and at its lower end into an opening 13 in the top of a cross-fitting 14, the lower opening 15 in which has screwed into it a threaded pipe section 16 which latter is screwed at its lower end into an opening 17 in a T-fitting 18 screwed on the upper end of a pipe 19, supported as hereinafter described, the oil pipe 12 extending downwardly through, and in spaced relation to, the hollow members just described and laterally outward through an opening 20 in the T-fitting 18 and 100 through a pipe 21 screwed into the opening 20, this pipe thence leading to a suitable supply of fuel oil.

105 The manifold section 4 contains a passage 22 opening at its opposite ends through the base plate 3, and terminating midway between the ends of the manifold in a down-

wardly opening portion 23 arranged directly over, and concentric with, the generator plate 9, the purpose of providing this manifold being to direct air, which rises upwardly through its inlets and thence passes downwardly through the passage 23 and which thus becomes heated, to the generator plate 9 for mixture with the oil supplied to this plate.

10 The burner also comprises a pair of pipes 24 each of inverted U-shape which are located at opposite sides of the manifold 4 and each of which opens at both ends downwardly through the base plate 3. One end of each of 15 the U-pipes 24 is left open, whereas the other ends of these pipes open into the pipes 25 which in turn open into the fitting 13, the purpose of the pipes just referred to being to conduct air entering them through their lower 20 open ends, through the heated portions of these pipes and thence into the space surrounding the oil pipe 12 for heating the oil in the pipe 12 in its passage to the generator plate and furnishing a supply of heated air below 25 and around the burner head, the air discharging through the ports 8, and supplementary to that supplied to the generator plate from above through the manifold 4.

The outer end of the pipe 21 is shown as 30 provided with a hollow head 26 through which the pipe 12 extends, this head containing an opening 27 located in position to discharge oil overflowing the burner head, into the drip bucket 28 of drip-bucket-controlled 35 mechanism provided to automatically shut off the flow of oil to the pipe 12 in case of overflow of oil from the burner, the bucket 28 being shown as hung on an end of a trip lever 29 controlling a shut-off valve represented at 30 controlling the supplying of oil through the pipe 12 as is well known in the art.

The burner structure shown also comprises a supporting base 31 having an upwardly extending socket 32 into which the lower end of 45 the pipe 19 extends and to which it is secured, to permit of its vertical adjustment, by a set-screw 33. The base 31 is provided with vertically adjustable legs 34 shown as set-screws arranged in triangular form at which the base 50 rests upon the part on which it is to be supported, the adjustable legs 34 affording means whereby the base plate 3 and the parts carried thereby may be caused to extend in level position, regardless of the position occupied by 55 the support upon which the base 31 rests.

Referring now to those features of the construction shown which constitute my invention, the apparatus illustrated also comprises a frame member 35 of the same shape in plan 60 as the base plate 3 and provided along its sides with a continuous upwardly opening recess, or channel, 36, into which an endless flange-member 37 depending from the marginal edges of the base plate 3 loosely extends permitting of tilting movement of the base plate

3 on the frame 35, and forming in effect a relatively loose telescopic joint between these parts.

The frame 35 is supported on standards 38 shown as rising from a base plate 39 in a triangular arrangement, the base plate 39 being adapted to be seated on the floor of the ash pit of the furnace to be equipped with the apparatus. The standards shown are each formed of a lower tube section 40 and an upper rod section 41 loosely telescoped therewith, with the lower end of the latter threaded, as represented at 42 for engagement with a nut 43 which rests on the upper end of the tube 40 and by the adjustment of which on the rod 41 varies the elevation of these rods, these adjustable supporting means permitting the frame 35 to be substantially horizontally positioned in the furnace, such as that represented at 44 and in which the apparatus is shown 85 installed.

In the arrangement shown the frame 35 in the installing of the apparatus in a furnace and which is positioned therein to be spaced at all sides from the side walls of the furnace shown, is sealed therein to close the space around the frame 35, as by cement, represented at 45 which is poured upon a mold-bottom-forming member 46 located in the space between the frame and the furnace walls, the cement when it hardens 90 permanently sealing the frame 35 in place.

As a convenient means for supporting the member 46 during the pouring of the cement I provide on the frame 35, to radiate from the center thereof, threaded studs 47 which are slidable in radially disposed openings 48 in the frame 35 and extend loosely through slots 37^a in the flange 37 of the base 3 when the base is assembled with the frame 35, these studs having nuts 49 screwed thereon and extending at the outer and inner sides, respectively, of the frame 35. In the insertion of the frame to position in the furnace, usually through the ash pit opening at the front of the furnace, the studs 47 are preliminarily adjusted inwardly toward the center of the frame 35 and after the member 46 is applied to encircling position about the frame 35, the studs 47 are adjusted outwardly to the position shown, to form seats for the member 46, whereupon the cement 45 is poured sealing all of these parts in place.

In the arrangement shown the base plate 39 is of such size that it furnishes a support upon which the feet 34 rest and against which the latter are adjustable.

The base plate 3 of the burner structure and carrying the generator plate 9 to be leveled, being tiltably adjustable relative to the frame 35 in the permanently sealed condition of the latter, may be adjusted at will either to initially, or subsequently, level it, and by reason of the loose telescopic joint between the base plate 3 and the frame 35 such adjustment may be made without danger of opening the joint

between these parts and permitting of the leakage of air upwardly therethrough.

While I have illustrated and described a particular construction embodying my invention, I do not wish to be understood as intending to limit it thereto as the same may be variously modified and altered without departing from the spirit of my invention.

What I claim as new, and desire to secure 10 by Letters Patent, is:

1. In burner apparatus, the combination of a frame-member for location in a furnace to be equipped with the apparatus and in which it is to be permanently held preventing adjustment thereof, means supporting said frame-member on the floor and adjustable for positioning said frame-member substantially horizontally, a burner-structure comprising a member required to be positioned 15 in horizontal position for proper functioning located in the opening in said frame-member and shiftable relative to said frame-member in the set position of the latter, and sealing means at the joint between said members 20 operative in the different positions of said second-named member for preventing the flow of air upwardly through said joint.

2. In burner apparatus, the combination of a frame-member for location in a furnace to 30 be equipped with the apparatus and in which it is to be permanently held preventing adjustment thereof, and a burner-structure comprising a member required to be positioned in horizontal position for proper functioning located in the opening in said frame-member with a telescopic sealing-joint between said members, said last-named member being shiftable, at said joint, relative to 35 said frame-member in the set position of the latter.

3. In burner apparatus, the combination of a frame-member for location in a furnace to be equipped with the apparatus and in which it is to be permanently held preventing 45 adjustment thereof, means supporting said frame-member on the floor and adjustable for positioning said frame-member substantially horizontally, and a burner-structure comprising a member required to be positioned in horizontal position for proper functioning located in the opening in said frame-member with a telescopic sealing-joint between said members, said last-named member being shiftable, at said joint, relative to 50 said frame-member in the set position of the latter.

4. In burner apparatus, the combination of a frame-member for location in a furnace to be equipped with the apparatus and in which it is to be permanently held preventing 60 adjustment thereof, a burner-structure comprising a member required to be positioned in horizontal position for proper functioning located in the opening in said frame-member, said last-named member being shiftable 65 relative to said frame-member in the set posi-

tion of the latter, means supporting said second-named member on the floor and adjustable for shifting said second-named member into desired level position, and sealing means at the joint between said members operative 70 in the different positions of said second-named member for preventing the flow of air upwardly through said joint.

5. In burner apparatus, the combination of a frame-member for location in a furnace 75 to be equipped with the apparatus and in which it is to be permanently held preventing adjustment thereof, means supporting said frame-member on the floor and adjustable for positioning said frame-member substantially horizontally, a burner-structure comprising a member required to be positioned 80 in horizontal position for proper functioning located in the opening in said frame-member, said last-named member being shiftable relative to said frame-member in the set position of the latter, means supporting said second-named member on the floor and adjustable for shifting said second-named member into 85 desired level position, and sealing means at the joint between said members operative in the different positions of said second-named member for preventing the flow of air upwardly through said joint.

6. In burner apparatus, the combination of a frame-member for location in a furnace to be equipped with the apparatus and in which it is to be permanently held preventing adjustment thereof, a burner-structure comprising a member required to be positioned 90 in horizontal position for proper functioning located in the opening in said frame-member with a telescopic sealing-joint between said members, said last-named member being shiftable, at said joint, relative to 95 said frame-member in the set position of the latter, and means supporting said second-named member on the floor and adjustable for shifting said second-named member into 100 desired level position.

7. In burner apparatus, the combination of a frame-member for location in a furnace to be equipped with the apparatus and in which it is to be permanently held preventing adjustment thereof, means supporting said frame-member on the floor and adjustable for positioning said frame-member substantially horizontally, a burner-structure comprising a member required to be positioned 115 in horizontal position for proper functioning located in the opening in said frame-member with a telescopic sealing-joint between said members, said last-named member being shiftable, at said joint, relative to said frame-member in the set position of the latter, and means supporting said second-named member on the floor and adjustable for shifting said second-named member into 120 desired level position.

8. In burner apparatus, the combination of 125

- 5 a frame-member for location in a furnace to be equipped with the apparatus and in which it is to be permanently held preventing adjustment thereof, said frame-member containing an endless groove, and a burner-structure comprising a member required to be positioned in horizontal position for proper functioning located in the opening in said frame-member and having a flange extending 10 loosely in said groove to adapt said last-named member to be tiltably adjusted relative to said frame-member, and means holding said last-named member in adjusted position.
- 15 9. In burner apparatus, the combination of a frame-member for location in a furnace to be equipped with the apparatus and in which it is to be permanently held preventing adjustment thereof, means supporting said frame-member on the floor and adjustable for positioning said frame-member substantially horizontally, said frame-member containing an upwardly-opening endless groove, and a burner structure comprising a member 20 required to be positioned in horizontal position for proper functioning located in the opening in said frame-member and having a depending flange extending loosely in said groove to adapt said last-named member to be tiltably adjusted relative to said frame-member, and means supporting said last-named member on the floor and adjustable for shifting said second-named member into desired level position.
- 25 10. In combination with a furnace, a frame-member located therein in spaced relation to the furnace-walls and tiltably adjustably supported to permit it to be positioned substantially horizontally, a mold-bottom-forming member located in the space between said frame-member and the furnace-walls, a series of supports for said mold-bottom-forming member on said frame-member, said supports being inwardly displaceable to permit assembly of the parts and outwardly displaceable to position said supports for functioning, cementitious material on said mold-bottom-forming member and filling the space between said frame-member and the furnace-walls, and a burner structure comprising a member required to be positioned in horizontal position for proper functioning located in the opening in said frame-member and tiltably adjustably supported relative to the 30 set position of said frame-member.
- 35 11. In a furnace structure, the combination of a burner structure located in the furnace and comprising a member required to be positioned horizontally for proper functioning and shiftable to so position it, a second member containing an opening in which said first-named member is located and
- 40
- 45
- 50
- 55
- 60

in which it is shiftable and sealing means at the joint between said members and operative in the different positions of adjustment 65 of said first-named member for preventing flow of air upwardly through the joint around said member.

12. In burner apparatus, the combination of a frame-member for location in a furnace 70 to be equipped with the apparatus and in which it is to be permanently held preventing adjustment thereof, a burner-structure comprising a member required to be positioned in horizontal position for proper functioning 75 located in the opening in said frame member and shiftable relative to said frame member in the set position of the latter, and sealing means at the joint between said members operative in the different positions of adjustment 80 of said second-named member for preventing flow of air upwardly through said joint.

13. In a furnace structure, the combination of its combustion chamber having a portion projecting inwardly from its side walls and presenting an opening, a burner structure located in said opening and comprising a member required to be positioned horizontally 90 for proper functioning and shiftable in said opening, and sealing means at the joint between said member and the wall of said opening operative in the different positions of adjustment of said member to maintain said joint closed. 95

14. In a furnace structure, the combination of a burner structure located in the furnace and comprising a member required to be positioned horizontally for proper functioning, and a telescopic sealing-joint surrounding said member and operative in the different positions of adjustment of said member for preventing flow of air upwardly 100 around the latter, said member being shiftable, at said joint to adapt it for horizontal 105 positioning.

15. In a furnace structure, the combination of a burner structure located in the furnace and comprising a member required to be positioned in horizontal position for proper functioning and shiftable to so position it, and sealing means operative in the different positions of adjustment of said member for preventing flow of air upwardly 110 through the joint around said member comprising endless flanges one of which is operatively connected with said member and the other of which is relatively stationary and carried by the furnace structure, said flanges being loosely telescoped with each other to permit said member to be adjusted as above 115 stated at said joint. 120

ALBERT BODDEKER.
